UNITED STATES PATENT OFFICE.

FRANK C. SCHLITZER, OF BUFFALO, NEW YORK.

EASEL FOR SHOWCARDS.

Application filed July 13, 1923. Serial No. 651,257.

To all whom it may concern:

Be it known that I, FRANK C. SCHLITZER, a citizen of the United States, residing at Buffalo, in the county of Erie and State of New York, have invented a new and useful Improvement in Easel for Showcards, of which the following is a specification.

This invention relates to an easel for supporting show cards, display signs or the like.

Such easels are usually constructed of cardboard or similar material so that they may be compactly folded for convenient storage and transportation and readily unfolded when required for supporting the article with which they are associated. In the forms of these easels as heretofore constructed the main upright standard, prop or brace plate connected at its front edge 20 with the show card would in time bend or curl laterally at its rear end due to the effects of changes in temperature and weather conditions which resulted in impairing the stability of the easel and reducing its effectiveness as a support for the show card or the like mounted thereon so that the same is liable to fall or collapse.

It is the purpose of this invention to provide an easel which has its standard, prop or leg provided with means whereby the rear edge of the same is held in a rearwardly projecting position from the show card and restrained against lateral deflection and also to provide a firm support for the lower end 25 of the easel so that the same is capable of maintaining the show card or the like constantly in an upright normal position without any liability of the same tumbling over.

In the accompanying drawing: Figure 1 is a perspective view showing my improved easel applied to a show card or sign. Figure 2 is a horizontal section taken on line 2—2 of Figure 1. Figure 3 is a fragmentary vertical section taken on line 3—3 of Figure 1. Figure 4 is a plan view of a blank from 45 which the easel embodying my invention is constructed.

Similar characters of reference indicate like parts in the several figures of the drawings.

My improved easel is constructed of a single sheet of cardboard or other suitable flat material similar to the easels now commonly used and is provided with an upwardly tapering standard, prop or brace 10 of plate form which is adapted to be connected at its

front edge with the rear side of a show card 11 or the like and project rearwardly therefrom and rest at its lower end on the table, shelf, counter, or other available surface. 60 The connection between the standard and the show card may be accomplished in any suitable manner, for instance as shown in the drawings, this may be effected by providing the front edge of the standard with an upright attaching flange or flap 12 which is attached to the rear side of the show card by cement or the like and is foldably connected with the standard along an upright creased or scored line 13. The standard may 70 be folded and unfolded relatively to the show card by swinging over the crease line 13 as a hinge and the same may be held in its unfolded position by one or more locking lips 14 which are formed in the blank at the 75 corner between the standard and attaching flange and each of which is adapted to project rearwardly and engage a slit 15 in the adjacent edge portion of the standard for holding the standard at right angles to the 80 attaching flange and show card.

In the absence of any provision to prevent it the rear portion of the standard, instead of remaining in a position at right angles to the show card, will become bent, curled or deflected laterally under the action of heat, moisture or atmospheric conditions, which if permitted to occur would reduce the stability of the easel and possibly permit the show card to fall over and thus destroy its 90 advertising value.

To avoid this the rear edge of the standard is stiffened or reinforced by providing the same with an upright stiffening flange or flap 16 which is connected with the body 95 of the standard by a hinge joint extending along a creased or scored line 17 whereby this flange may be folded and unfolded in a horizontal direction. When unfolded so as to project from the standard at right 100 angles or substantially so relatively thereto this operates to stiffen or strengthen the standard and prevent the same from bending, curling or deflecting out of its normal position at right angles to the show card 105 and thus maintaining a firm support for the same. In the preferred construction the stiffening flange tapers toward its upper end, thereby furnishing the greatest reinforcing or strengthening effect to the lower 110 end of the standard where the same is most needed and gradually reducing this stiffen-

ing effect toward the upper end of the standard in the same measure as less reinforcing of the standard is required.

- It is desirable to employ some means for holding the stiffening flange in its folded operative condition which means preferably consist of a locking hook 18 cut out of the stock or body forming the standard and adapted to be bent laterally therefrom on a creased or scored line 19 and provided at its rear end with a beak 20 which engages with the rear side of the stiffening flange and holds the same at an angle to the standard. The creased line 19 is preferably inclined so that the same rises from its front end toward its rear end and thereby permits of forming a comparatively large hook and still leave a substantial amount of stock between the opening forming the hook and the creased line 19, as shown at 21, so as to avoid weakening the standard at this point and instead maintaining the same sufficiently strong to enable the same to resist warping out of shape while in use.
- In order to extend or increase the base area of the standard at the lower end of the same and thus increase the stability of the same and insure maintenance of the display card in its upright position the lower end of the standard is provided with a supporting flange 22 which is adapted to be folded or unfolded vertically relatively to the standard along a horizontal creased or scored line 23 between the same. When the easel is not in use this supporting flange is unfolded and flush with the standard, as shown in Figure 4, and when in use the same projects laterally from the standard so that it can rest on a suitable surface. This supporting flange preferably tapers forwardly so that it is widest at the rear edge of the standard where the same is most needed and narrowest adjacent to the front edge of the standard where the same is less necessary.

This easel requires practically no more material than one of ordinary construction which does not possess the advantageous

features of the present improvements. The blank for the same can be cut with one operation of a die so that its cost of production is not increased. Furthermore this easel when once set up requires no further attention as the same is not liable to fall down, which is an important consideration in show window displays where the advertising value of a show card or sign is materially enhanced if the sign is not liable to topple over and disarrange the wares displayed and will permit of maintaining them in an orderly and well arranged manner.

I claim as my invention:

1. An easel for supporting a show card constructed of a sheet of material, comprising an upright standard adapted to be connected at its front edge to the show card and to project rearwardly therefrom and provided at its rear upright edge with a horizontally foldable stiffening flange which is joined therewith by a creased line, and means for holding said stiffening flange in its operative position, comprising a locking hook stamped wholly out of the stock of said standard and having a rearwardly projecting beak which is adapted to engage the edge of said flange.

2. An easel for supporting a show card constructed of a sheet of material, comprising an upright standard adapted to be connected at its front edge to the show card and to project rearwardly therefrom and provided at its rear upright edge with a horizontally foldable stiffening flange which is joined therewith by a creased line, and means for holding said stiffening flange in its operative position, comprising a locking hook stamped out of the stock of said standard and having a rearwardly projecting beak which is adapted to engage the edge of said flange, and the base of said hook being connected with the body of said standard by a creased line which is inclined and rises from its front end toward its rear end.

In testimony whereof I affix my signature.
FRANK C. SCHLITZER.
